RESERVOIR FOR ULTRASONIC INHALATION THERAPY

Walter Levine, Lincolnwood, Ill., assignor to Inhalation Therapy Equipment, Inc., Chicago, Ill.

Filed Aug. 25, 1975, Ser. No. 607,118

Term of patent 14 years

Int. Cl. D24—04

U.S. Cl. D83—1 N

FIG. 1

FIG. 2

FIG. 4

FIG. 3

FIG.5

FIG. 1 is a front elevational view of a reservoir for ultrasonic inhalation therapy showing my new design, the rear elevational view being a mirror image thereof; FIG. 2 is a side elevational view from the right side of FIG. 1;

FIG. 3 is a top plan view of the embodiment of FIG. 1; FIG. 4 is a side elevational view from the left side of FIG. 1; and

FIG. 5 is a perspective view of modified embodiment of the reservoir illustrated in FIG. 1.

I claim:

The ornamental design for a reservoir for ultrasonic inhalation therapy, as shown and described.
